TOMLINSON FORT JOHNSON, JR., OF ATLANTA, GEORGIA.

CLAMP FOR ELECTRICAL CONDUCTORS.

Application filed July 6, 1921. Serial No. 482,750.

To all whom it may concern:

Be it known that I, TOMLINSON F. JOHNSON, Jr., a citizen of the United States, residing at Atlanta, in the county of Fulton 5 and State of Georgia, have invented new and useful Improvements in Clamps for Electrical Conductors, of which the following is a specification.

This invention has reference to clamps for use in connection with electric installations, and its object is to provide a clamp to be applied to an electric line conductor for coupling the latter to another conductor, where it is desired, for instance, to couple a branch 10 conductor, or a switch, or a lightning arrester, or some other electrical device to the line conductor for feeding such device temporarily, or semi-permanently from the line conductor.

It has heretofore been proposed to employ 15 clamps for connecting up jumper or other conductors to a main line conductor, especially temporarily, but such clamps, on account of their construction, have been adapted for light duty only, while the present invention is so designed that it may be employed for heavy duty. In order to accomplish this purpose the heavy duty clamp is made devoid of springs, because the heat 20 generated by the electric current passing through the springs is liable to render the springs useless.

The heavy duty clamp is not only springless, but is capable of carrying much heavier 25 currents than clamps as heretofore made, while very much better contact between the clamp and the main line conductor is obtained. Moreover, the clamp is easier and cheaper to build than one having springs in 30 its make-up, and can be sold at a lower price, besides withstanding overheating due to over-loads which would ruin a spring clamp.

In accordance with the invention the clamp is made up of two jaws, having an 35 extent of separation to grip a line conductor between them, these jaws being hinged together at one end without a positive connection therebetween, further than the presence of a screw bolt having a threaded stem extending through a threaded passage in one 40 jaw and an enlarged smooth passage in the other jaw, with one jaw guided by the other jaw. Adjacent to the threaded bolt the jaws are traversed by a loop of wire, with the terminals of the loop twisted together to pre-

vent accidental separation of the jaws. Moreover, one jaw of the clamp has wings thereon to serve as guides for the other jaw, and the wingless jaw has studs thereon permitting engagement by the eye-bolt. Furthermore, the jaw with the studs thereon contains a socket with a set screw for attaching a jumper wire to the clamp, and at the end of the last-named jaw, remote from the eye-bolt, is another eye, for the application of a manipulating stick for handling the clamp to apply it to, or disengage it from, a line conductor.

The invention will be best understood from a consideration of the accompanying drawing, forming part of this specification, with the understanding, however, that the invention is not confined to any strict conformity with the showing of the drawing, but may be changed and modified, so long as such changes and modifications mark no material departure from the salient features of the invention, as expressed in the appended claims.

In the drawings:

Figure 1 is a front elevation of a clamp embodying the invention and shown applied to a line conductor, and with a manipulating stick indicated in dotted lines as associated with the clamp.

Figure 2 is a rear elevation of the clamp shown in Figure 1.

Figure 3 is a side elevation of the clamp also indicating the manipulating stick.

Figure 4 is an upright central section of the upper end of the clamp applied to the line conductor.

In the drawing, there is shown a clamp composed of two jaw members 1 and 2, having at one end coacting separable ends 3, 4, with one end 3 provided with side wings 5, loosely embracing the sides of the end 4, one end interfitting the other to prevent any material lateral movement of the members relative to each other. The connections between the two members may be described as a hinge connection though there is no pivot between the parts.

In order to provide a certain amount of play between the ends 3 and 4, the two jaw members have spaced matched perforations 6, through which there is threaded a wire loop 7, with the ends twisted together, as indicated at 8, to constitute a safety tie wire. The member 1 is of generally rectan-

gular outline throughout the greater portion of its area with the end 3 contracted in width, and the other end, shown at 9, in the form of a socket, designed to receive a 5 jumper or other wire conductor 10 held in the socket by a set screw 11. The end 9 terminates in an eye 12 projecting at an angle to the length of the member 1, and designed to receive a manipulating horn

10 13 carried by a head 14, fast to one end of a manipulating stick 15, which forms the subject matter of another application for Letters Patent filed of even date herewith.

Associated with the member 1 is the member 2 of approximately the same shape, but having oppositely disposed shoulders 16, of somewhat greater spread than the body of the member 1, said shoulders having outstanding tapered lugs 16^a which embrace 20 the sides of the member 1 and serve as guides. The shoulders and lugs are in transverse alignment with the clamping means for the members.

In order to impart strength to both members while reducing their weight, they are 25 preferably made of web-and-flange form. The two members 1 and 2 have registering openings, which are traversed by a screw stem or shank 17, terminating at one end 30 in an eye 18, wherefore the shank and eye constitute an eye-bolt, while the free end of the shank 17 is upset as shown at 19 to prevent the eye-bolt from being fully unscrewed. The opening 1^a in the member 1 35 is longer in diameter than the diameter of the shank 17 and is unthreaded, while the opening 2^a in the member 2 is threaded so as to be engaged by the threads of said shank.

40 The headed end 19 and the wire loop 7 prevent separation of the two members 1 and 2, to an extent which might cause the accidental dropping of one of the members. The member 2 terminates at the end remote 45 from the end 4 in a prolonged tail 20, curving away to some extent from the socket 9, whereby the socket 9 and tail 20 form a converging entrance to the clamp, directing the clamp toward the line wire so that 50 the clamp and line wire may be located in a recess 21 of the member 1, designed to seat the line wire, which latter is indicated at 22.

Between the eye 18 and the shank 17 of 55 the eye-bolt, there is provided a circumferential shoulder 23 to engage lugs 24 projecting from the corresponding face of the member 1, so that the eye-bolt 17, 18, may rock to a limited extent with reference to 60 the member 1, without subjecting the screw stem 17 to harmful strains.

When it is desired to couple up the clamp with the line conductor 22, or other carrier of current, the manipulating stick 15 is 65 attached to the clamp by passing a horn

13 through the eye 18, with the bolt 17 partly unscrewed, so that there is room enough between the jaws 1 and 2 to permit the application of the clamp to the conductor 22. Now, by rotating said stick 15 about 70 its longitudinal axis, the eye-bolt 17, 18, may be turned, so as to screw the members 1 and 2 together, with a heavy pressure between the members.

By this means, a greatly improved contact is made between the clamp and the line wire and the clamp will readily carry more current than is the case with a clamp of similar construction where the contact depends upon the strength of springs. In the 80 case where a spring-held clamp is relied upon, heating will occur should a heavy current be transmitted through the clamp, and such heating is quickly destructive to the spring and to the degree of contact pressure 85 obtained. With this invention, the contact is only limited by the area of engagement and the pressure of the contact, and even should the overload be very pronounced, no harm can occur for there is no condition 90 established by the overheating which would tend to draw the temper of the springs.

It will be noted that the wings 5 are provided on the jaw member 1, while the lugs 16^a are formed on jaw member 2, so that the 95 two members are respectively embraced, on the one hand by the wings and on the other by the lugs.

The clamp structure is easier and cheaper to build than other clamp structures of like 100 nature, and can therefore be sold at a lower price in competition with such other clamp structures.

The claims of this application are generic to the invention disclosed in my later application, Serial No. 611,790, which application embodies a further improvement on the type of clamp disclosed herein.

What is claimed is:—

1. A springless clamp for electrical conductors, comprising two associated jaw members with an interfitting loose engagement at one end, and at the other end of the clamp provided with a mouth for receiving an electric line conductor, and a bolt screw-threaded through one jaw member and terminating beyond the other jaw member in a manipulating eye, whereby it may be turned from a distance.

2. A springless clamp for electrical conductors, comprising two associated jaw members with an interfitting loose engagement between them at one end, consisting of a pair of wings on one member loosely embracing the sides of the other member, and at the other end provided with a mouth for receiving an electric line conductor, said members being coactively shaped to seat the line conductor, and a bolt screw-threaded at one end through one 120

- jaw member and freely traversing an unthreaded opening of the other jaw member, and at the other end terminating in a turning means.
5. A springless clamp for electrical conductors, comprising two associated jaw members having an interfitting connection at one end and provided with matching openings, connecting means for the jaw members traversing said openings, and a bolt adjacent to the connecting means, said bolt being threaded through one jaw member and freely traversing the other jaw member, and at the outer end terminating in a turning means adapted to receive a manipulating device.
10. A clamp for electrical conductors, comprising two associated jaw members having an interfitting loose engagement at one end and provided with matching perforations, a wire loop traversing the perforations and having the ends twisted together to form an elongated loop, and a clamping means for the jaw members to cause the latter to bind upon a line conductor lodged between them.
15. A springless clamp for electrical conductors, comprising two associated jaw members with an interfitting loose connection at one end, and at the other end diverging to form an entrance or mouth for receiving a line conductor, a bolt screw-threaded through one member and passing through an opening of the other member, said bolt being located between the loose connection and the portion of the clamp which engages the line conductor, and guiding means on one member to overlap the other member, whereby to prevent lateral movement of the members with respect to each other.
20. A springless clamp for electrical conductors, comprising two elongated associated jaw members with a loose connection at one end and diverging at the other end to receive a line conductor, one of the members being formed with a seat for the line conductor and with a socket to receive a jumper conductor, and adjacent to the socket being formed with an eye for a manipulating device, means on one member for preventing lateral movement of the other member with respect thereto, and a bolt screw-threaded through one member and loosely traversing the other member and terminating at the end remote from the threaded portion in a manipulating eye.
25. A springless clamp for electrical conductors having coacting jaw members to embrace a line conductor, with one member provided with a socket at one end to receive a jumper conductor, and having means to hold the jumper conductor in place, an elongated loop traversing the jaws to hold them loosely together, and a clamp screw also traversing the jaws and having means at one end for manipulating the clamp screw from a distance.
30. A springless clamp for electrical conductors, having means at one end for the attachment of the jumper conductor, a loose interfitting connection at the other end, with the first-named end of the clamp having diverging extensions to facilitate the placing of the clamp in operative relation to a line conductor, means on the clamp at an intermediate point of its length to engage a line conductor, and means for securing the clamp to the line conductor comprising a screw arranged to bind the clamp in embracing relation to the line conductor, and provided with an eye at one end adapted to receive a manipulating device operable from a distance.
35. A springless clamp for electrical conductors, comprising two jaw members having a seat for a line conductor, means at one end of the members forming an entrance or mouth for the insertion of the line conductor, means to prevent relative lateral movement of the members, means at the other end for loosely engaging the members, and a clamp screw for drawing the two members together for clamping said conductor, said screw having a manipulating means at one end.
40. A springless clamp for electrical conductors, comprising two members having their upper ends interfitting, with one end provided with wings loosely embracing the sides of the other member, lugs provided on said other member and loosely embracing the member having the wings, a seat for a line conductor provided in one of said members, and a screw for connecting said members and clamping said conductor.
45. A springless clamp for electrical conductors, comprising two associated jaw members with a loose interfitting engagement between them at one end and at the other end provided with a mouth for receiving an electric line conductor, said members being coactively shaped to seat the line conductor, and a bolt having a screw-threaded connection at one end with one jaw member and passed through an unthreaded opening of the other jaw member, and at the other end terminating in a turning means, said bolt having an annular shoulder at an intermediate point of its length, and spaced diametrically-disposed lugs on one of the jaw members to be engaged by said shoulder, whereby the bolt may rock to a limited extent.
50. A springless clamp for electrical conductors, comprising two associated jaw members having a mouth for receiving an electric line conductor, said members being

shaped to seat the said conductor, and means for securing the clamp to the line conductor, comprising a screw arranged to bind the clamp in embracing relation to the line conductor, said screw being provided at the outer end with a turning means and at a point between the turning means and the

other end with an annular shoulder, and lugs on one of the jaw members to be engaged by said shoulders.

In testimony that I claim the foregoing as my own, I have hereto affixed my signature.

TOMLINSON FORT JOHNSON, JR.
